UNITED STATES PATENT OFFICE.

HERBERT K. FOSTER, OF RIVERSIDE, NEW JERSEY, ASSIGNOR TO THE KEYSTONE WATCH CASE COMPANY, OF RIVERSIDE, NEW JERSEY, A CORPORATION OF PENNSYLVANIA.

DESIGN FOR A WATCHCASE APPENDAGE.

Application filed April 3, 1925. Serial No. 13,012. Term of patent 14 years.

To all whom it may concern:

Be it known that I, HERBERT K. FOSTER, a citizen of the United States of America, residing at Riverside, in the county of Burlington and State of New Jersey, have invented a new, original, and ornamental Design for Watchcase Appendage, of which the following is a specification, reference being had to the accompanying drawing, forming a part thereof,

In the drawing,

I claim:

The ornamental design for a watchcase appendage as shown.

HERBERT K. FOSTER.
